UNITED STATES PATENT OFFICE.

FORREST M. KEETON, OF DETROIT, MICHIGAN.

DESIGN FOR A VEHICLE-WHEEL CHOCK.

6,285.

Specification for Design. Patented Sept. 14, 1920.

Application filed April 23, 1920. Serial No. 376,149. Term of patent 14 years.

To all whom it may concern:

Be it known that I, FORREST M. KEETON, a citizen of the United States, residing at Detroit, in the county of Wayne and State of Michigan, have invented a new and original Design for Vehicle-Wheel Chocks, of which the following is a specification, reference being had to the accompanying drawing, forming part thereof.

The figure of the drawing is a perspective of my vehicle wheel chock.

I claim:

The design for a vehicle wheel chock as shown in the figure of the drawing.

FORREST M. KEETON.
